UNITED STATES PATENT OFFICE.

HARRY BLAND STRANGE, OF BLACKHEATH, ENGLAND, ASSIGNOR TO THOS. FIRTH
AND SONS LIMITED, OF SHEFFIELD, ENGLAND.

ARMOR-PIERCING PROJECTILE.

1,166,093.

Specification of Letters Patent.

Patented Dec. 28, 1915.

Application filed April 12, 1915. Serial No. 20,963.

To all whom it may concern:

Be it known that I, HARRY BLAND STRANGE, subject of the King of England, residing at Blackheath, Kent, in England, have invented certain new and useful Improvements in Armor-Piercing Projectiles, of which the following is a specification.

This invention relates to armor-piercing projectiles and has particular reference to 10 projectiles of the type which are provided with a liner wherein is contained the bursting charge.

A projectile according to this invention is furnished with a liner which is capable 15 of moving longitudinally on the shock of impact in the cavity which contains it and between the liner and an inner casing which contains the explosive, elastic or compressible material is provided. The shape of the 20 cavity containing the liner and the shape and size of the liner itself are such that when the liner moves forward on the shock of impact it is compressed or slightly distorted, this action breaking the force of impact on the liner, and the provision of the 25 elastic or compressible material between the liner and the inner casing permits this compression or distortion to take place without dangerous pressure being exerted on the explosive. The rear or base of the liner conveniently fits into a coned or tapered seating 30 so that on the shock of discharge sufficient friction is set up to prevent the rotation of the liner.

Another feature of the liner according to 35 this invention is that it forms an entirely closed envelop for the explosive and is not rigidly connected to the shell body so that the liner may remain intact even if the shell 40 body be fractured on impact.

The accompanying drawing is a central longitudinal section through one construction 45 of armor-piercing projectile according to this invention the point of the projectile being broken away.

The shell body A is formed with a cavity to contain a liner B which however in its 50 normal position as shown in the drawing does not extend so far as the forward end A' of the cavity. The liner B is provided with a central screwed plug or partition C provided with holes or passages C' and acting

to divide the liner into two compartments. Each of these compartments is furnished with an inner casing D, for example of 55 papier mâché or other suitable material adapted to contain the explosive with which the shell is charged and a packing E of cork or other yielding substance of an elastic or compressible nature is provided between the 60 forward inner casing D and the interior of the liner.

The rear end of the liner is slightly coned on the outside as at B' to fit into a coned or tapered recess or seating in a screw plug A² 65 which closes the rear end of the shell, the central portion of this plug A² accommodates a fuse F which may be of any convenient construction and is provided with a gaine or casing F' projecting through the 70 base B² of the liner B into a central space made to receive it in the rear inner casing D. It will be seen that the base B² screws into the liner B which thus forms a closed envelop for the explosive and is without any 75 rigid connection to the shell body A. This is advantageous as the liner can remain intact even if the shell body is fractured.

The bursting charge in the rear inner casing D is ignited by the explosion consequent on the detonation of the charge contained within the gaine or casing F' of the fuse F. On the shock of discharge the liner B tends to set back and there is sufficient friction between its conical base B' and the 80 tapered seating in the end plug A² of the shell to prevent the liner from any rotary movement relatively to the shell. On impact occurring the liner moves forward in the cavity its front end being somewhat 85 compressed or distorted on entering the end or nose A' of the cavity. This compression or distortion is prevented from having any injurious effect on the explosive contained in the inner casing D by the packing of cork 90 or other elastic or compressible material E.

As previously mentioned the shock of impact is sufficient to disengage the gaine or casing F' of the fuse from the fuse body F and thus the casing F' moves forward with 95 100 the liner so that the explosive charge which it contains remains in the proper position relatively to the bursting charge in the rear inner casing D.

What I claim as my invention and desire to secure by Letters Patent is:—

1. In a projectile, the combination with the body hollowed to form a chamber, of a casing containing the explosive charge longitudinally movable within the chamber with a free space between the forward end of the casing and the forward end of the chamber having frictionally contacting surfaces, and deformable material at the forward end of the charge casing adapted to be deformed into the free space on impact of the projectile by contact with the wall of the chamber, whereby shock of impact on the charge 15 will be absorbed.
2. In a projectile, the combination with the body hollowed to form a chamber, of a casing containing the explosive charge longitudinally movable within the chamber with a free space between the forward end of the casing and forward end of the chamber, and deformable material at the forward end of the casing in frictional engagement with the walls of the chamber, the size and shape of the chamber and casing being such that on impact of the projectile the deformable material will be deformed into the free space and the shock of impact on the charge absorbed.
3. In a projectile, the combination with the body hollowed to form a chamber, of a casing containing the charge capable of longitudinal movement in the chamber on impact of projectile, said chamber and casing having direct frictional contacting surfaces whereby shock of impact on the casing will be absorbed.
4. In a projectile the combination with a body hollowed to form a chamber, of a casing containing the explosive charge movable longitudinally within the chamber on impact of the projectile, the casing and chamber having frictionally contacting surfaces, said chamber and casing being so shaped as that frictional resistance to the forward movement of the casing increases as the casing advances.
5. In a projectile, the combination with the body hollowed to form a chamber, of a casing of deformable material containing the explosive charge longitudinally movable in the chamber with a free space between the forward end of the casing and forward end of the chamber into which space the material of the casing at the forward end may be deformed on impact of the projectile, and a yielding material interposed between the casing and the charge at the forward end of the casing.
6. In a projectile, the combination of a body hollowed to form a chamber, the diameter of which is less at its forward end, of a casing containing the explosive charge within the chamber of less length than the

chamber, said casing being of less diameter at its forward end, the casing and chamber having frictionally contacting surfaces, explosive material disposed within the casing, and a packing of yielding material disposed at and around the forward part of the explosive within the casing.

7. In a projectile the combination of a body hollowed to form a chamber the diameter of which is less at its forward end, a liner within the cavity of this chamber of less length than the chamber and like the chamber of less diameter at its forward end, explosive material disposed in the liner a wrapping inclosing the explosive material, and a packing of a yielding substance disposed at and around the forward part of the explosive between the wrapping inclosing the explosive and the liner as set forth.

8. In a projectile the combination with a body hollowed to form a chamber, a liner which so fits the cavity of this chamber as to permit of forward movement of the liner within the chamber on impact of the projectile, a plug having an internally coned surface closing the rear end of the chamber, a coned surface at the rear of the liner adapted to engage the coned surface of the plug, a layer of a yielding substance within the forward part of the liner, and explosive material disposed in the liner with the yielding substance enwrapping its forward end as set forth.

9. In a projectile the combination of a body hollowed to form a chamber, a plug inclosing the rear end of this chamber, a liner of deformable material which so fits the cavity of the chamber as to permit of forward movement of the liner within the chamber on impact of the projectile and be deformed at its forward end, a plug closing the rear end of the liner which thus forms an envelop for the explosive which is entirely closed and not rigidly connected to the shell body, a layer of a yielding substance in the forward end of the liner, and explosive material disposed in the liner with the yielding substance enwrapping its forward end as set forth.

10. In a projectile the combination of a body hollowed to form a chamber, a plug closing the rear end of this chamber and having an internally coned surface, a fuse carried in the plug, a liner which so fits the cavity of the chamber in the shell body as to permit forward movement of the liner within the chamber on impact of the projectile, a plug closing the rear end of the liner except for an opening through which the fuse passes, an externally coned rear end to the liner adapted to engage the coned portion of the plug closing the base of the shell body, a perforated partition secured within the liner intermediate of its length and di-

viding the interior of the liner into forward and rear chambers, a layer of a yielding substance covering the interior of the liner forward of the partition and massed at the fore end, explosive material disposed in the forward chamber of the liner with the yielding substance between it and the liner, and explosive material disposed in the rear chamber of the liner and surrounding the in-

wardly projecting part of the fuse as set forth.

In testimony whereof I have signed my name to this specification in the presence of two subscribing witnesses.

HARRY BLAND STRANGE.
